Inventor

J. Francis Booraem

By his Attorney G. P. Gaerel

UNITED STATES PATENT OFFICE.

JOHN FRANCIS BOORAEM, OF GREENWICH, CONNECTICUT.

INCLINATION INDICATOR FOR AIRPLANES.

Application filed June 19, 1919. Serial No. 305,365.

To all whom it may concern:

Be it known that I, JOHN FRANCIS BOORAEM, a citizen of the United States, and a resident of Greenwich, in the county of 5 Fairfield and State of Connecticut, have invented certain new and useful Improvements in Inclination Indicators for Airplanes, of which the following is a specification.

10 The present invention relates to inclination indicators particularly for airplanes and has for an object to provide a device of this character which will indicate the position of the airplane at all times and in all 15 positions relatively to the earth whether the same is flying upright, upside down or at an angle of lateral or vertical inclination.

With these and other objects in view, embodiments of my invention are shown in the 20 accompanying drawings, and these embodiments will be hereinafter more fully described with reference thereto and the invention will be finally pointed out in the claims.

25 In the accompanying drawings:

Figure 1 is a side elevation of one form of my invention.

Figure 2 is a similar view showing the position of the same when the supporting structure i. e. the airplane, is at an inclination;

30 Figure 3 is a similar view showing the position of the same when the supporting structure is inverted;

Figure 4 is a view partly in section, of a 35 modified form of construction in which baffles are provided interiorly for the purpose of controlling the action of the indicating means;

Figure 5 is a vertical sectional view of 40 another modified form of construction;

Figure 6 is a side elevation, partly in section, of the form of the device shown in Figure 4, and with the device inclined and the colored liquid body overlapping the dif- 45 ferently colored upper half of the globe, and

Figure 7 is a side elevation of the nested baffle discs removed from the globe, the view being taken at right angles to Figure 6.

Similar reference characters indicate cor- 50 responding parts throughout the several figures of the drawings.

Referring to the drawings and more particularly to Figures 1 to 3 thereof, the embodiment of my invention shown therein 55 comprises a spherical globe 10 preferably transparent and formed of glass, the outer

surface being divided into suitably marked meridian circles, said circles passing through the poles *a*—*b* at the ends of the horizontal directional axis parallel to the line of horizontal flight when the airplane is flying forwardly in a horizontal line and also passing through the poles of the transverse axis *c* at right angles to the directional axis and in the same plane. Within the globe there is 60 provided a hemispherical liquid body 11, preferably of mercury in a liquid state at normal temperature, this body adapted by gravity to maintain a constant position relatively to the earth's center. The upper half 65 of the globe 10 is colored as for instance, red, and the globe is supported in suitable fixtures 12 and 13 mounted upon the fuselage of the airplane. The meridian lines, it will be understood, indicate the degree of 70 deflection of the airplane and the line of flying which deviates either way from the horizontal, and as soon as there is any deviation the edge of the colored portion of the globe at one side of the turning axis will be 75 raised relatively to the upper surface of the body 11 while at the other side it will extend below the upper surface of the body 11 thereby clearly indicating that there is an 80 inclination of flight.

Figure 2 illustrates the position of the device when the airplane is inclined downwardly head on, while Figure 3 illustrates the position when the airplane is inverted as in performing a loop or when flying upside 85 down. It is well known that such upside down flights may occur without the intention of the fliers and without their realization that they are flying upside down.

In Figure 4, I have illustrated a modified 90 form of construction in which baffles are provided within the globe for the purpose of controlling the flow of the liquid body therein so that the position of the liquid body will indicate the mean rather than the extreme 95 positions of the airplane as for instance when swaying or pitching in a gale. These baffles consist of a plurality of circular plates 14 intersecting the directional axis and also a plurality of circular plates 15 intersecting 100 the transverse axis at right angles thereto and in the same plane, these plates being provided with perforations 16 to permit of the retarded flow of the liquid body within 105 the globe.

The peripheries of these plates may be 110 coincident with the meridian markings upon

the exterior surface of the globe. In Figure 5 I have illustrated another modified form of construction in which an inner globe 17 is provided within the outer globe 18 forming an annular space therebetween, the said space being bridged by a plurality of baffles 19 and 20. An annular hemisphere 21 of mercury or other suitable liquid is provided within the said space, perforations 22 in the 10 baffles permitting flow of the liquid throughout the annular space. A light 30 is provided within the inner sphere.

From the foregoing it will be seen that my invention contemplates an indicator which 15 will clearly show at all times the position of the airplane in an unmistakable and graphic manner.

I have illustrated and described preferred 20 and satisfactory embodiments of my invention but it is obvious that changes may be made therein within the spirit and scope thereof as defined in the appended claims.

I claim:

1. An inclination indicator for airplanes 25 comprising a hollow spherical transparent globe provided with meridian markings, a

plurality of circular plates fitted within said hollow globe and lying in intersecting planes marked off by the meridian lines, said plates provided with openings therethrough, and a liquid body filling substantially the lower hemisphere and adapted by gravity to maintain a constant position relatively to the earth's center, said body being colored.

2. An inclination indicator for airplanes 30 comprising a hollow spherical transparent globe having meridian markings passing through a horizontal axis and provided with a suitable color on its upper hemisphere, a body of colored liquid supported in the lower hemisphere and adapted to occupy a constant position with respect to the earth's center, and a plurality of circular plates mounted within said sphere in intersecting planes marked off by meridian markings on 40 the sphere, said circular plates having series of openings near their edges to dampen oscillation of the body of liquid.

In testimony that he claims the foregoing as his invention, he has signed his name 45 hereunder.

J. FRANCIS BOORAEM.
